GAS FIRED WATER HEATER

Application filed May 11, 1929. Serial No. 362,308.

This invention relates to gas fired water heaters of the storage type.

The principal object of the invention is to provide a heater of relatively simple and inexpensive construction in which the heat available in the gas burned therein may be utilized with the highest practicable efficiency.

The features of this simple, inexpensive and highly efficient heater are shown in the drawings, in which:—

Figure 1 is a sectional view of the water heater structure.

Figure 2 is a sectional view on the line 2—2 of Figure 1.

Figure 3 is a sectional view on the line 3—3 of Figure 1.

Figure 4 is an enlarged view of a section indicated by dotted outline in Figure 1.

In Figures 1 and 2 a water containing tank 5 with a vertical tube 7 extending through it is shown placed concentrically within an insulating casing 6 with an annular space 15 and an upper space 13 between them, and both supported in any suitable manner as by a base 24.

The bottom of the annular space 15 opens into a vent 16 shown equipped with a draft hood 16a.

A burner 9, preferably having raised flame ports to permit complete aeration of the gas and flame and burning the gas in a relatively high flame and large volume for a given burner area, for operation by hand or any suitable automatic means, and supported in any suitable manner as by a bracket 22, is shown with the flame 8 extending well within the tube 7.

At 9a is indicated a heat radiating element for increasing the amount of heat transferred by radiation to the tube 7, said element 9a being of any suitable heat radiating material and relatively vertically elongated so as to extend up into the lower portion of the tube 7.

This radiating element is preferably in the form of a truncated cone substantially as shown in Figure 1 with the small end down and positioned within the circle of flame ports, said lower end of said element having a smaller diameter than the flame port circle

so as to permit the aeration and partial burning of the gas before it strikes the radiating material. The flame is thus brought into intimate contact with and licks the heat radiating material and any small projections thereon as indicated in 9a and raises it to a relatively high temperature.

Combustion of the gas is thereby accelerated and completed and a sufficiently large proportion of the total heat is liberated in radiant form to insure the relatively even heating of the water throughout the tank.

Burners adapted for the use of high pressure gas with a suitable air inspirator or for an air blast may be used when desired for further increasing the rate of gas burning in a given heater. Such burners are preferably of the radiant type so a substantial amount of the heat in the gas burned may be liberated as radiant heat and be immediately absorbed by the water through the tube wall at the lower portion thereof.

Secondary air to the burner may be limited by any suitable means as an opening 11 in the bottom plate 10 or placing the burner of a sufficiently large area close to or into the tube for restricting the opening as desired.

Water outlet and inlet pipes are indicated by 20 and 21 respectively.

A core buster 17 of any suitable design is shown disposed in the tube 7 supported as by a pin 19 and centered by pins 18.

A condensation drain may be used as indicated at 23.

In Figure 3 a tank 5 is shown placed eccentrically within the insulating casing 6. The annular space 15 is narrowed near the flue outlet 16 and gradually enlarges to a maximum width opposite the flue outlet. This arrangement further assures the uniform descent of the gases around the tank and the utilization of the heating surface provided in the water tank wall by equalizing any tendency for the gases to short circuit from the top opening of tube 7 at 12 to the flue opening 16.

In Figure 4 the curved arrows "a" indicate the movement of the gas particles toward the water tank 5 in their downward travel in the annular space 15. The arrows "b" indicate

the relative velocity and temperature of the gas particles in the annular space: the longer the arrows the greater the velocity and the lower the temperature of the gas particles.

- 6 The particles closest to the water tank have the lowest temperature and the greatest downward velocity.

In the operation of the heater, the heat radiated by the flame 8 and radiant burner 10 9 and 9a is immediately absorbed by the water through the tube 7. The burned gases in passing upwardly through the tube are continually cooling and the coolest portion of the gas column is that close or next to the tube 15 wall. As this cooling progresses, and the density of the gas particles increases these cooler particles move more and more slowly and tend to have a downward direction in relation to the more rapidly rising and hotter 20 gases in the center of the gas column.

A relatively cool thick insulating layer of gas is thereby interposed between the hot gases and the tube column.

The thickness of this cool gas layer is reduced by increasing the velocity of the gases through the tube by means of a core buster 17 which diminishes the gas passage area. The burned gases accordingly have a greater upward velocity around the core buster, the 30 thickness of the insulating film near the tube is reduced and the rate of heat transfer is increased.

The burned gases pass out of the tube at the top 12 and over the tank through space 13 and 35 downwardly around the outside of the tank through annular space 15 and thence out through vent 16.

The gases descend in a relatively uniform manner around the tank in the annular space 40 15 with the cooler gas particles near the tank wall continually descending at a relatively high velocity whereby the hotter gas particles are continually drawn toward the tank surface with a relatively high rate of heat transfer and a nearly complete absorption of the 45 heat in the gases by the tank wall and water before the gases are discharged through the outlet 16.

By referring to the Figures 1 and 2, it will 50 be observed that the heating surface provided by the tank wall in the down draft passage between the tank 5 and insulation 6 is substantially greater than that in the up draft passage in the tube 7.

55 With gases descending around the tank wall, provision is made for a relatively high rate of heat transfer to the water through the relatively large tank wall area in this down draft passage.

60 The heating surface in the down draft passage is accordingly adapted for the absorption of so much heat from the burned gases that these gases may leave the up draft passageway substantially above the dew point of any water vapor in them. The for-

mation or depositing of condensates in the up draft passage is thereby avoided.

By again referring to Figures 1 and 2 it will be observed that the cross sectional area of the tube 7 for the up draft is substantially 70 less than the cross sectional area of the down draft passage provided between the tank 5 and the insulation 6.

By reason of the difference in the areas of these passages for the products of combustion and the higher temperature of the up draft gases the upward movement of the products of combustion within the tube 7 is faster than the rate of down travel in the 75 outer passage.

80 Because of this higher velocity the insulating effect of the gas film between the rising column of hot gases and the tube wall as previously described is reduced and may be further reduced by the use of a core buster 85 as above described.

As the gases are cooling as they are rising in this up draft passageway a proportionately greater amount of heat is transferred in the lower portion of this tube than in the 90 top which reduces the rate of transfer as the gases rise in the tube and the water in the lower portion of the tank receives more heat than that in the upper portion.

In the down draft passageway with its 95 greater amount of heating surface and as the gases descend as they are cooling and provide for a relatively high rate of heat transfer in this passage, the gases are hottest at the top and as a result less and less heat is 100 available and transmitted to the water as these gases descend around the tank.

The heat radiating element in the lower portion of the tube increases the heat transfer to the water in the lower portion of the 105 tank and with the heat transferred to the water in the up draft passage from the sensible heat of the burned gases offsets the high rate of heating the water in the top portion of the tank by the gases in the down draft 110 passageway and relatively even heating of the water throughout the tank is thereby effected.

With heat radiating material used in any desired amount the proportion of the total 115 heat of the gas burned liberated as radiant heat and absorbed through the tube in the lower portion of the tank may be varied within relatively wide limits and the water temperatures in the top and bottom of the 120 tank may be thereby kept within the limits desired.

The invention accordingly provides simple and highly efficient means for recovering the 125 radiant heat from the flame; increasing the amount of heat liberated as radiant heat in the burner and core buster zones and the immediate recovery thereof in the water; increasing the velocity of the burned gases in the tube and the rate of heat transfer there- 130

in; the relatively uniform descent of the burned gases around the water containing tank with a constantly diminishing temperature to the flue outlet. As the function of the burner element 9a is to receive heat on its exterior from the flame and to transmit the same by direct radiation, it will be evident that a heat radiating element of this character is applicable to any type of water heater in which a tubular structure of any type is employed to transmit heat to a surrounding body of water or other liquid.

10 The apparatus as described is simple, inexpensive, easy to manufacture, and provides highly efficient means for heating water with 15 gas.

Having described my invention, I claim:

1. A gas fired water heater comprising: a water storage tank having a vertically arranged tube therein extending therethrough and providing an uptake passage; a heat insulating casing enclosing said tank and spaced therefrom along the sides and at the top and thereby providing a downtake passage in communication with the uptake passage; said downtake passage having an outlet in the lower portion thereof; a gas burner at the bottom of said tube; and a heat radiating element disposed within the lower portion of said tube, the heat received by said element from the burner being radiated directly to the lower portions of the tube and the products of combustion passing upwardly through the tube and thence downwardly around the tank to said outlet, the uptake passage provided by said tube and the downtake passage being so related as to produce a more rapid upward flow of the products of combustion therethrough than in the downtake passage around the tank.

2. A gas fired water heater comprising: a water storage tank having a vertically arranged tube therein extending therethrough and providing an uptake passage; a heat insulating casing enclosing said tank and spaced therefrom along the sides and at the top and thereby providing a downtake passage in communication with the uptake passage, said downtake passage having an outlet in the lower portion thereof; a gas burner at the bottom of said tube; and a heat radiating element disposed within the lower portion of said tube, the heat received by said element from the burner being radiated directly to the lower portions of the tube and the products of combustion passing upwardly through the tube and thence downwardly around the tank to said outlet, the heating surface areas in the uptake passage provided by said tube being less than in the downtake passage and said heat radiating element being so related to said areas that the water is heated to a relatively uniform temperature throughout the tank.

3. In a water heater of the storage type

having communicating passages for the upward and downward flow of the products of combustion, the area of the heat transfer surface for direct heating by the products of combustion in said uptake passage being materially less than the area of the heat transfer surface for direct heating by the products of combustion in said downtake passage, said downtake passage having an outlet in the lower portion thereof; said uptake passage 75 having a gas burner at the bottom thereof, and a heat radiating element disposed within the lower portion thereof, the heat received by said element from the burner being radiated directly to the lower portions of the 80 said uptake passage and the products of combustion passing upwardly through the uptake passage and thence downwardly through the downtake passage to said outlet, whereby the water is heated to a relatively 85 uniform temperature throughout the tank and the products of combustion are caused to enter said downtake passage at a temperature above the condensation point of the water vapor therein.

In testimony whereof I affix my signature.
HIRAM J. CARSON.
